Primary Examiner — Mitchell Siegel*(74) Attorney, Agent, or Firm* — Young Basile**CLAIM**

(57) The ornamental design for a button maker, as shown and described.

DESCRIPTION

FIG. 1 is a perspective view of a button maker showing my new design;

FIG. 2 is a top plan view thereof;

FIG. 3 is a front view thereof;

FIG. 4 is a rear view thereof;

FIG. 5 is a left-side view thereof; and,

FIG. 6 is a right-side view thereof.

The broken lines in FIGS. 1-3 are illustrative of environmental structure only and form no part of the claimed design.
